UNITED STATES PATENT OFFICE.

EDWARD JAMES KIRK, OF BRACEBRIDGE, CANADA.

HAT OR CAP RACK.

SPECIFICATION forming part of Letters Patent No. 645,362, dated March 13, 1900.

Application filed November 11, 1898. Serial No. 696,167. (No model.)

To all whom it may concern:

Be it known that I, EDWARD JAMES KIRK, of the town of Bracebridge, in the district of Muskoka, Canada, have invented certain new 5 and useful Improvements in Hat or Cap Racks, of which the following is a specification.

This invention relates to hat and cap racks; and the object in view is to provide a light, 10 strong, and ornamental rack adapted particularly for use in stores for displaying goods, such as hats and caps, the rack embodying means whereby the several hangers or hat and cap supports or hooks may be adjusted 15 relatively to each other and with relation to the supporting-frame, so as to economize space and adapt the rack as a whole to articles of different sizes. The rack also affords an open-work or skeleton horizontal shelf 20 upon which to place various objects for display to customers, and the hanger-frames are of such construction that each one of them will support a number of articles where they may be advantageously displayed without 25 necessitating the taking down of the articles for the various customers.

The detailed objects and advantages of the invention will appear more fully in the course of the ensuing description.

30 The invention consists in a display-rack for hats, caps, &c., embodying certain novel features and details of construction and arrangement of parts, as hereinafter fully described, illustrated in the drawings, and incorporated in the claims.

In the accompanying drawings, Figure 1 is a perspective view of a display-rack constructed in accordance with the present invention. Fig. 2 is a vertical cross-section 40 through the same. Fig. 3 is a detail perspective view of one of the hanger-frames.

Similar letters of reference designate corresponding parts in all the figures of the drawings.

45 The display-rack contemplated in this invention comprises, essentially, two parallel rods A, which are connected by end cross-bars B, thus forming a rectangular frame in which the parallel rods and end bars are relatively rigid. When the supporting-frame comprised by the rods A and bars B is in position for use, the several rods and bars are disposed in a common horizontal plane. The end bars B are also connected by means

of longitudinal wires or strands G, arranged 55 at suitable intervals and connected at their extremities to eyes I, projecting inwardly from the bars B. In this manner an open-work or skeleton horizontal supporting-frame is provided, which when hung in a store 60 forms a light, strong, and durable shelf upon which the articles to be displayed may be placed or from which they may be hung.

In connection with the supporting-frame hereinabove described I employ a series of 65 hanger-frames or holders C, each of which is formed of a single length of wire. The central portion of the wire is allowed to remain straight, or approximately so, to form what may be termed a "cross-bar" E. After forming the bar E the end portions of the wire are bent to form loops or eyes F and then extended outward and bent back upon themselves, as shown at J, to form hooks D. Other eyes F are then formed, which lie in alignment with the eyes F above referred to, and the terminals are then extended inward convergently, as shown at K, and curved to form oppositely-projecting hooks H, which lie between the vertical planes of the eyes F and 80 which are offset from and below the horizontal or common plane of the eyes F. The hooks H are connected at the nearest point of their approach by a tie or brace L.

The several hanger-frames or holders are 85 strung upon the rods A, the latter passing through the eyes F of said frames. Any number of hanger-frames may be thus strung upon the supporting-frame and may be adjusted so as to bring them at the required distances 90 from each other. When properly positioned, they are held in their relative positions by means of the longitudinal wires or strands G, which are looped around the cross-bars E, as shown at M. The cross-bars E thus form additional or intermediate supports for the longitudinal wires or strands G, thus adding to the efficiency of the supporting-frame as a shelf upon which to place articles for display. 95

From the foregoing description it will be 100 seen that I have produced a simple, light, durable, and convenient rack for supporting various articles for display in stores, &c., and that the device as a whole may be produced and sold at a small cost. The supporting-frame may be made of any desired length, and any required number of hanger-frames may be strung thereon. It will also be seen that 105

the distances between the several hanger-frames may be varied according to the will of the manufacturer and that the several hanger-frames may be adjusted with relation to each other by simply removing the wires or strands G. This will enable the hanger-frames to be readjusted to suit requirements, and after they are adjusted they may be retained in such positions by again applying the wires or strands G in a manner that will be readily understood. It will also be seen that each hanger-frame is provided with oppositely-extending hooks which project beyond the parallel rods A of the supporting-frame and that it is further provided with additional oppositely-projecting hooks which are arranged between the vertical planes of the parallel rods and which are offset from and below the common or horizontal plane of said rods, thus providing a very compact arrangement of supporting-hooks. It will also be seen that the cross-bars A are in effect provided with terminal eyes F, which encircle the rods A, thereby serving as a means for supporting the hanger-frames upon the supporting-frame and at the same time bracing the parallel rods of the supporting-frame, the cross-bars also serving as intermediate supports for the longitudinal wires or strands G, which constitute a portion of the supporting-surface for the articles which are placed upon the supporting-frame. The device as a whole will accommodate a large number of articles, including hats, caps, &c., and all the articles may be displayed to advantage, thereby avoiding the necessity of removing or taking down the various articles to exhibit them to customers. It also obviates the usual practice of piling the hats and caps upon each other, which is liable to result in injury thereto.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described the invention, what is claimed, and desired to be secured by Letters Patent, is—

1. As a hat and cap rack, two rods connected by cross-bars in combination with a series of wire frames bent to form hooks, and also eyes or loops by means of which they are strung upon the said rods; and wires connecting the said frames and the cross-bars, substantially as and for the purpose specified.

2. As a hat and cap rack two rods A, connected by the cross-bars B, in combination with a series of wire frames C, each bent to form the hooks D, the cross-bar E, the eyes or loops F; and one or more wires G, connecting the said frames and cross-bars, substantially as and for the purpose specified.

3. As a hat and cap rack two rods A, connected by the cross-bars B, in combination with a series of wire frames C, each bent to form the hooks D, the cross-bar E, the eyes or loops F, and hooks H; and one or more wires G, connecting the said frames and cross-bars, substantially as and for the purpose specified.

4. A display-rack substantially such as described comprising a series of end-supported rods arranged parallel to each other, in the same transverse plane, and forming a supporting-shelf, and a series of hanger-frames applied to said rods, each hanger-frame having a pair of hooks connected by an intermediate bar and said hooks extended in opposite directions from the respective sides of the supporting-shelf formed by the rods, said hanger-frame also provided with oppositely-facing hooks disposed below and within the first-named hooks, as and for the purposes set forth.

5. A display-rack, substantially such as described comprising a series of parallel rods forming a supporting-shelf, means connected to end portions of said rods for holding the same, and a series of hanger-frames applied to said rods and each having the cross-bar, the upper pair of hooks, the downwardly-converging branches, and the lower pair of oppositely-facing hooks disposed within the upper hooks; the cross-bar of each hanger-frame lying substantially in the transverse plane of the shelf-forming rods and the upper pair of hooks extended in opposite directions from the respective sides of the shelf afforded by said rods, as and for the purposes described.

6. A display-rack, substantially such as described, comprising straight cross-bars, a series of rods attached thereto in the same transverse plane and forming a supporting-shelf, and a series of hanger-frames having cross-bars spanning the spaces between the rods and constituting a part of the area of the shelf, each hanger-frame being also provided with a plurality of hooks, two of which are prolonged beyond the opposite sides of the shelf afforded by the rods and certain other hooks disposed below the shelf, as set forth.

7. A rack comprising parallel rods suitably supported, in combination with frames strung thereon and each made of a single length of wire bent to form a cross-bar with terminal eyes to receive the rods, and hooks beyond the eyes, the terminals of the wire being extended toward each other to form other hooks which project in opposite directions and lie between the planes of the rods, substantially as and for the purpose specified.

Bracebridge, Canada, November 5, 1898.

EDWARD JAMES KIRK.
